UNITED STATES PATENT OFFICE.

CASSIUS MERCILUS COCHRAN, OF MARION, INDIANA.

COMBINED STEP-LADDER AND IRONING-BOARD.

SPECIFICATION forming part of Letters Patent No. 548,960, dated October 29, 1895.

Application filed February 28, 1895. Serial No. 540,026. (No model.)

To all whom it may concern:

Be it known that, I CASSIUS MERCILUS COCHRAN, a citizen of the United States of America, residing at Marion, in the county of Grant and State of Indiana, have invented certain new and useful Improvements in a Combined Step-Ladder and Ironing-Board; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to provide an article of furniture which can be used as a step-ladder and as an ironing-board; and it consists in the construction and combination of the parts, as will be hereinafter fully set forth, and particularly pointed out in the claims.

In the accompanying drawings, forming part of this specification, Figure 1 is a perspective view showing the device arranged as a step-ladder, and Fig. 2 is a perspective view showing the parts in position to present an ironing-board.

A A designate a pair of legs or supports which are each preferably made up of two strips or bars a and a' to provide lightness, and between the legs or supports are secured steps or rungs A' . The upper ends of the strips a and a' , which make up the legs or supports A, are connected to each other by a cross-bar a^2 , the ends of which project beyond the legs or supports. Between the strips a and a' at a suitable distance below their upper ends are secured blocks a^3 , which, in connection with the upper step, serve as bearings for a cross-bar A^2 , to which is pivoted a swinging support hereinafter described. The strips or bars a' are provided with blocks or catches a^4 and a^5 , as shown.

B B designate two parallel strips which are connected to each other near one end by a cross-piece b and at the other end by a cross-piece or board b' , the projecting edge of the board b' being supported by triangular blocks b^2 , which also provide bearings for the projecting ends of the cross-bar a^2 in pivotally connecting the parts to each other. The strips B

are provided on their inner edges with longitudinal grooves b^3 , and on their inner sides are secured blocks b^4 , which are apertured to provide bearings for a cross-bar B' . To the outer ends of this cross-bar are connected links C carrying a cross-bar c , which is adapted to engage with the blocks a^4 when the device is used as a step-ladder, and with the blocks a^5 when the device is used as an ironing-board. To the outer ends of the cross-bar c are pivoted links C' , which are pivoted at their other ends to the side pieces d of the swinging platform or support D, said platform or support consisting of the side pieces d , to the outer ends of which are secured a transverse board D', the inner ends of the side pieces being pivotally connected to the projecting ends of the cross-bar A^2 , hereinbefore referred to.

To the inner side of the strips B are pivoted a number of bars e , which are adapted to be swung outward to serve as clothes-racks when the device is used as an ironing-board.

B^2 designates a board which is adapted to be slid between the strips B to complete the ironing-board proper, and this board B^2 is provided on its edges with tongues b^6 , which fit the grooves b^3 .

In constructing the device the links C and C' should be of such a length that the platform or support D can be swung over the upper end of the device, so that the parts can be arranged, as shown in Fig. 1, to form a step-ladder, the cross-bar c being in engagement with the blocks or catches a^4 , and when swung back over the end of the device and the cross-bar c placed in engagement with the blocks or catches a^5 the parts will then be in position to present an ironing board or table, the platform or frame D acting as supporting-legs.

It will be understood that when the device is used as a step-ladder the board B^2 is removed to lighten the structure, and is readily slid into place when the device is to be used as an ironing-board. It will also be understood that the weight of the parts serves to hold the cross-bar c in engagement with the blocks or catches a^4 and a^5 .

I am aware that prior to my invention it has been proposed to combine in one article of furniture a step-ladder and ironing-board, and therefore do not claim such combination broadly; but

What I claim as new, and desire to secure by Letters Patent, is—

1. The combination, of two sets of legs pivotally connected to each other, one of the sets 5 of legs carrying steps; bars C and d pivotally connected to the legs, and to each other by links C', the bars C being connected by a cross-bar c and the bars d by a board D', together with blocks or catches carried by one 10 set of legs, the parts being organized substantially as shown, whereby they may be adjusted to different positions to provide either a step-ladder or ironing-board.
2. The combination, of the strips B B connected to each other so as to be maintained 15 parallel for the purpose of receiving a remov-

able board, blocks b² and b⁴ secured to the strips B B; legs A A pivotally attached to the blocks b² and provided with catches a⁴ and a⁵, bars d d pivotally connected to the legs 20 A A; together with links C C pivoted to the blocks b⁴, said links having a cross-bar for engagement with the catches; and links C' pivotally connected to the bars d and to the links C C, substantially as shown and for the 25 purpose set forth.

In testimony whereof I affix my signature in presence of two witnesses.

CASSIUS MERCILUS COCHRAN.
